UNITED STATES PATENT OFFICE.

FRANCIS STEPHEN HEFFERNAN, OF SPRINGFIELD, MISSOURI.

NON-REFILLABLE BOTTLE.

SPECIFICATION forming part of Letters Patent No. 784,941, dated March 14, 1905.

Application filed April 22, 1904. Serial No. 204,492.

To all whom it may concern:

Be it known that I, FRANCIS STEPHEN HEFFERNAN, a citizen of the United States, residing at Springfield, in the county of Greene and State of Missouri, have invented certain new and useful Improvements in Non-Refillable Bottles, of which the following is a specification.

My invention relates to an improved form of check-valve adapted particularly for use in connection with bottles to prevent the refilling of the same, but which may be used for other purposes.

In the accompanying drawings, which illustrate my invention, Figure 1 is a central vertical section through a bottle having my improved stopper and check-valve arranged therein. Fig. 2 is a similar view through the upper part of the bottle inverted. Fig. 3 is a section on the line A B of Fig. 1. Fig. 4 is a section on the line C D of Fig. 1 looking downward; and Figs. 5, 6, and 7 are elevations of the check-valve, valve-seat, and the body of the stopper, respectively.

Referring to the drawings, A indicates a bottle which may be of any usual form, and A' indicates the neck of the bottle, within which is arranged a stopper comprising a body portion or plug B, having a cavity 1, within which is arranged a check-valve C, the purpose of the check-valve being to permit the outflow of liquid from the bottle and to prevent refilling of the same. An outlet-opening or bore 2 extends from the cavity 1 to the upper or outer end of the body of the stopper, and an opening or port 3 extends centrally through a valve-seat 4 at the inner or lower end of the stopper, connecting the cavity 1 with the interior of the bottle. The cavity 1 is tubular, and the valve C is circular in cross-section and fits closely within the walls of the cavity, but is free to move longitudinally therein when the bottle is inverted. The upper side of the valve is concaved or dished, as indicated by the numeral 5, and a circular series of ports or openings 6 extend from this concave face of the valve through to its lower side. The combined cross-sectional areas of the ports 6 are preferably made equal to the cross-sectional area of the open-

ing 2 or the port 3. A projection 7 on the lower face of the check-valve normally fits within and closes the port 3, and the remainder of the lower surface of the valve is perfectly flat, as shown, so that when the valve 55 is against its seat the ports 6 in the valve will be closed thereby to prevent the admission of liquid through the valve into the bottle. When the bottle is inverted, however, as shown in Fig. 2, the valve leaves its seat by 60 the force of gravity or by the pressure of the liquid within the bottle, or both, and drops to the other end of the cavity 1. The flanges 5^a, which surround the concave face of the valve, then support the valve, and the liquid may flow 65 from the port 3 through the openings 6 in the valve, thence through the space or cavity 8 formed between the concave face of the valve and the outer or solid end of the stopper, and thence through the outlet-opening 2. The 70 space or cavity 8 may be enlarged by forming a recess 8^a in the body of the stopper, as shown.

In practice it will be understood that the bottle is first filled with liquid, and the stopper, complete with its check-valve, is then secured in position, after which the contents of the bottle may be poured out; but refilling will be prevented. In order to hold the stopper in place, the body portion B is provided 75 with an annular groove 9 and a longitudinal groove 10, extending from its outer end to said annular groove. The interior of the bottle-neck also has an annular groove 9^a and a longitudinal groove 10^a, which register with 80 the corresponding grooves 9 and 10 in the body of the stopper when the latter is in position. The stopper is held firmly in place and hermetically sealed by a liquid cementing or plastic material of any suitable kind, which 85 is poured into the registering grooves 10 and 10^a and flows into and fills the annular registering grooves 9 and 9^a. After the cementing material becomes hardened it will be seen that the stopper becomes permanently secured 90 in place by an air and liquid tight joint. The valve-seat 4 is similarly secured in place with in the lower end of the stopper-body by means of suitable cementing material poured into an 95 annular space 11 through an opening 12, said 100

space and opening being formed by registering grooves in the interior wall of the stopper-body and in the periphery of the valve-seat.

- 5 The stopper-body or plug and the valve when used in a bottle are preferably made of glass; but these parts, if desired, may be made of non-oxidizable metal or any other suitable material which will not be injuriously acted
10 upon by the liquid or which will not affect the liquid. It will also be apparent that the stopper-body and check-valve may be used in steam, water, and other pipes to permit the outflow of fluids and prevent the return flow,
15 and I do not wish to limit my invention to its use in connection with bottles, although it is so shown in the drawings.

Having described my invention, what I claim, and desire to secure by Letters Patent,
20 is—

In a device of the character described, a plug adapted to fit into a tubular body, said plug

having a cavity therein and an outlet-opening extending centrally from the outer end of said cavity to the outer end of the plug, and having also a flat valve-seat at its inner end provided with a central port, and a check-valve fitting closely within the lateral walls of said cavity, said valve having a concave outer face and an inner face adapted to fit against said valve-seat, and having one or more openings extending from its concave face to its inner face, said openings being out of line with the port and arranged so that their inner ends will be closed by the valve-seat in the normal 35 position of the valve.

Signed at Springfield, in the county of Greene and State of Missouri, this 19th day of April, 1904.

FRANCIS STEPHEN HEFFERNAN.
